UNITED STATES PATENT OFFICE.

MICHAEL E. FRANK, OF SHEBOYGAN, WISCONSIN, ASSIGNOR OF ONE-THIRD TO LOUIS HERMAN, OF SHEBOYGAN, WISCONSIN.

BANK-PROTECTOR.

974,564.

Specification of Letters Patent. Patented Nov. 1, 1910.

Application filed February 24, 1910. Serial No. 545,675.

To all whom it may concern:

Be it known that I, MICHAEL E. FRANK, a citizen of the United States, and resident of Sheboygan, in the county of Sheboygan & State of Wisconsin, have invented certain new and useful Improvements in Bank-Protectors; and I do hereby declare that the following is a full, clear, and exact description thereof.

10 The object of my invention is to provide a simple and effective burglar trap equipment for buildings and also to insure the safety of the occupants thereof, the invention being especially applicable to banking institutions or the like, wherein the lives of the cashiers are frequently exposed and endangered by attacks from burglars during business hours.

In a broad sense the invention contemplates the use of either weight or spring-controlled closures for the various doorways and windows of the building, together with bullet-proof shields for the cashier's cage-windows, all being connected and under 25 foot-lever control, whereby any employee or person within the caged inclosure of the institution may release the entire series of door closures and shields, all of which will 30 instantaneously operate to close the foyer from entrance or exit to thus entrap the occupants thereof, which occupants are at the same time isolated from the caged portion of the institution, while at the same time the person of each cashier is protected 35 by the bullet-proof shield.

The invention therefore consists in various structural features and combination of parts to be fully set forth hereinafter with reference to the accompanying drawings 40 and subsequently claimed.

In the drawings Figure 1 represents a sectional elevation of a portion of a building embodying the features of my invention, the section being taken through the 45 main entrance of the building and a cashier's window; Fig. 2, a sectional plan view of the same; Fig. 3, an enlarged detail sectional view of a portion of a cashier's window, illustrating the mechanism of a bullet-proof shield for the same in its normal or locked position; Fig. 4, a detail cross-section of the same as indicated by line 4-4 of Fig. 3, and Fig. 5, a view in diagram of the entire mechanism, showing the system of 50 levers and their cable connections.

Referring by characters to the drawings, 1 represents the entrance-way of a building provided with a vestibule 2, which may or may not be equipped with swinging doors, but is provided with a sliding metallic door 3, which door is normally locked open in such position that its upper edge is flush with the floor line. The metallic door 3 is slidably mounted in ways 4, with which the side walls of the vestibule are provided, the 60 ways being preferably formed in boxes having weights 5 therein. The construction of this door is similar to the construction as shown in Fig. 3 of the drawings, in which view the window shield is illustrated. The 65 boxed weights 5, as shown in the diagram, being connected to the door 3 by flexible hangers 6, which hangers pass over pulleys 7 that are mounted within the boxes 4. The door 3 is held in its normal position by 70 means of a spring-controlled latch 8, the nose of which latch is adapted to engage an aperture 9 in the door, and, while I have shown the latch engaging an aperture as 75 stated, it is understood that the door may 80 be provided with lugs as a substitute therefor.

Referring especially to Fig. 1 and the diagram view Fig. 5, the spring-controlled latch 8 is connected by a rod or cable 10 to 85 an arm 11 of a lever 12, which lever is fulcrumed to a bracket 13 that is suspended from the ceiling of the room just beneath the main floor of the building. The lever 12 has a treadle extension 14 that extends up 90 through an aperture in the floor conveniently located adjacent to a cashier's window A, there being a spring 15 interposed between the treadle-head and floor. In order to conceal the treadle-head and also to 95 protect the same from being accidentally operated, I preferably incase said treadle with in a flexible shield 16, which shield is designed to conform to a standard cuspidor. To counterbalance the resistance of the various cable connections between the lever 13 and other parts of the mechanism the said lever is preferably provided with a counter-weight 17.

Incased within the caged partition wall 18 is a sliding bullet-proof shield or blind 19, the upper edge of which shield is normally flush with the sill of the cashier's window. As best shown in Fig. 3, the side edges of this shield are provided with roll- 105 110

ers 20 arranged to travel upon ways 21, which ways form one of the walls of boxes 22 within the partition wall 18. The boxes serve as housings for weights 23, which 5 weights are connected by cables or chains 24 to the upper portion of the shield, the cable being arranged to travel over rollers 25 within the boxes. The shield is normally locked down in opposition to the weights by 10 a spring-controlled trip-latch 26, which latch is fulcrumed within a bracket secured to the floor and provided with a nose that is adapted to engage an aperture in said shield. When the latch is released it is 15 obvious that the weights will cause said shield to immediately rise and close the cashier's window, it being understood that any form of slideable weight-controlled shield may be utilized for that shown. One 20 of the edges of the shield is shown as provided with a toothed rack 27, adapted to be engaged by a pawl 28. This pawl and ratchet is designed to lock the shield and thus prevent it being pushed back into the 25 partition after the same has once been released, such a precautionary mechanism being provided in some instances where it would be likely that a burglar may attempt 30 to force the shield back to its normal position in order to have access to the person of the cashier, or currency that may be located within the cage. A similar mechanism to this may be also utilized in connection with the doors or windows of the apartment. To 35 return the door or shield to its normal position, this pawl 28 can be retracted from toothed engagement with the rack by means of a handle 29 which extends outwardly through the partition and in a position accessible to persons within the cage. When 40 such a device is used in connection with a door as shown, the same may be located in the room below or, when used in connection with a window, the handle may be concealed 45 in such manner that it would be impossible for a burglar to locate the same. The shield 19 is so positioned in the cage partition that it will not interfere with the usual 50 barred grating 30, which grating as shown in Fig. 1, is located outside of said shield.

The cashier's desk is provided with a hinged metallic blind or lid 31, which lid is held closed by a spring-controlled latch 32 55 that engages a tongue 33 depending from said lid. The latch serves to lock the lid in opposition to a series of strong springs 34, which springs are suitably supported within the desk and arranged to impinge against 60 the lower face of said lid. By this arrangement it will be seen that when the latch 32 is released, the action of the springs will cause the lid to instantaneously swing upward upon its hinges and thus close the cashier's window. This lid, together with the

shield and doors previously mentioned, comprise a series of bullet-proof blinds which are designed to not only protect the employees of the institution, but also serve as a burglar trap. Owing to the strength of 70 the springs the closing action of the lid will be instantaneous and therefore insure immediate protection to the cashier against bullets or other weapons in the hands of a burglar within the foyer of the apartment, it being understood that the swinging lid will effect 75 the closure comparatively much quicker than would be obtained by the sliding shield. After the lid has been thrown upward it is secured by means of a locking member 35 and thus said lid cannot be returned to its 80 normal position except by an employee upon the inside of the cage or partition.

While I have shown and described the cashier's cage as being equipped with the 85 bullet-proof swinging desk lid and slideable shield, it is understood that in some instances for economy in construction, the shield may be dispensed with or vice versa.

When the shield 19 has been released to 90 effect a closure of the window, the lower portion of the body of the cashier is protected by utilizing a bullet-proof panel 36, which panel, as shown in Fig. 1, is located beneath the desk, but in instances where 95 metallic partitions are utilized the armored panel may be dispensed with.

As shown in Fig. 2 and the diagram Fig. 5, the room is equipped with three cashiers' 100 windows A, B and C, all of which windows are provided with a mechanism similar to that described in connection with the cashier's window A, with the exception that the levers 12^a and 12^b respectively of the last named windows are not provided with arms 11. This arm 11, as previously stated, is directly connected to the metallic door 3 which controls the main entrance of the building and, as shown in Fig. 2, a similar 105 sliding door 3^a is arranged in connection with the entrance to the inner caged compartment. This door 3^a is also connected by a cable 10^a to the cable 10, being passed over a guide-pulley 37. Thus it will be seen 110 that when the lever 12 under the cashier's window A is operated the door 3^a will also be released.

While I have shown and described the levers 12^a and 12^b as having no provision 115 for direct connection with the sliding doors 3 and 3^a, it is obvious that if desired the same may each be provided with a connection similar to that shown with reference to cashier's window A, but owing to the fact that when either of the last mentioned levers are actuated it is essential, that incidental to this movement, all of the mechanism must be set in motion, direct connection to the various doors for economy sake may be dispensed with.

130

With a view to instantaneous operation of all of the foot treadle levers when any one of the system have been depressed, I have shown a series of cable connections between 5 the series of levers, which is clearly illustrated in the diagram Fig. 5. In said diagram lever 12 is provided with an extension 38, which extension has connected thereto a cable that passes over a pulley a^1 and under a 10 pulley a^2 to a similar extension 38^a of the lever 12^a. A continuation a^3 of this cable passes over a cable a^4 to an idle guide-pulley a^5 , at which point the said cable makes a 15 right angle turn and passes under a pulley a^6 to an extension 38^b of the lever 12^b. A return cable b , which is connected to the extension 38^b, passes over a pulley b^1 to an idle guide-pulley b^2 , from which point this 20 cable extends at approximately a right angle under a pulley b^3 and is connected to the extension of lever 12^a. From this lever an extension b^4 of the cable passes over a pulley b^5 and under a pulley b^6 to the extension 38 of lever 12. Thus the series of 25 treadle levers irrespective of their relative positions are connected in such a manner that movement of any one of said levers will cause the other levers of the system to be moved in the same direction. By this arrangement 30 the lever 12 may be considered the master lever of the system and will thus actuate all sliding doors or windows of the building, it being understood that the windows (not shown) are equipped with blinds similar in 35 construction to the shields described in connection with the cashiers' windows.

From the foregoing description it will be seen that if a burglar should enter the foyer of the bank and make the slightest threatening movement toward a cashier, the latter can, without changing his position, touch the treadle-portion 14 of his lever and thus cause all of the cashiers' windows to be immediately closed, while at the same time the 40 metallic doors will close the various doorways and thus the burglar will be confined and isolated within the foyer so that he is effectually trapped and can be readily captured without endangering the lives of the 45 employees of the institution. Attention is also called to the fact that even should the burglar resort to firearms, the quickness with which the swinging lid of the cashier's desk can be brought to position will cause a 50 deflection of any bullets which may pass through the window. After the mechanism has been automatically released, it can be restored to its normal position by means of a central windlass 39, which windlass is conveniently placed within the cellar or beneath 55 the protected room. The windlass is swiveled upon a base and provided with suitable cable and pulley connections, which cable can readily be attached to the various metalic doors, whereby the same may be drawn 60

down to the position as shown in Fig. 1, it being also obvious that the shields are drawn down in a similar manner and, as shown in Fig. 1, each shield is provided with a section of cable 40, to which the windlass cable may be conveniently connected when the shields are in their released or closed position. Each foot-treadle, as best shown in Fig. 1, is also connected by a cable to the trip-dogs 26 and 32 controlling the shield and swinging lid, whereby depression of the lever will release the aforesaid shield and lid in the manner previously mentioned. 70

While I have shown and described various mechanisms in detail for accomplishing the desired result, it should be understood that I do not confine myself to any specific structural details for accomplishing the various movements incidental to the releasing operation, but it is preferable to actuate the series 80 of trip-latches positively by means of some direct wire or cable connections to the various levers for the reason that by using a positive mechanism of this character there is less liability of failure of the mechanism to operate in an emergency, but it should be understood that electrical release mechanism may be employed in some instances, and such electrical release mechanism is within the scope of my invention, as being means for 85 releasing the various protecting and trap mechanisms. 90

The operating weights comprising the actuating motors of the sliding shields and doors, while being shown in connection with 100 grooved pulleys and cables, are in practice connected by sprocket-wheels and chains in place of said grooved rollers, the last named construction being preferable for the reason that it is less liable to wear. 105

I claim:

1. In a commercial institution having a cashier's window, a protecting device comprising a bullet-proof blind for the window, a motor-controlled actuating mechanism in 110 connection with the bullet-proof blind, a locking-latch for the actuating mechanism, a treadle release lever for the latch and a flexible shield for concealing the operating extension of the treadle. 115

2. In a commercial institution having an inclosed cage, a series of cashiers' windows in the cage, a main doorway and a communicating doorway to the cashier's cage, a protecting device and burglar trap comprising 120 slideable blinds for the cashier windows and doorways, actuating weights for the blinds, spring-controlled hinged lids for the cashiers' windows, locking latches for the blinds and hinged lids, a foot treadle in juxtaposition to each cashier's window, and means connecting each foot-treadle with all of the locking latches. 125

3. In a commercial institution having a cashier's window, a protecting device com- 130

prising a spring-controlled bullet-proof hinged lid for the window, a locking-latch for the lid, and a foot-treadle in juxtaposition to the window, the foot-treadle being connected to the locking-latch.

4. In a commercial institution having an inclosed cage, a cashier's window, a main doorway, and a communicating door to the cashier's cage; a protecting device and burglar trap comprising slidable blinds for the cashier's window and doorways, actuating weights for the blinds, a motor-controlled hinged lid for the cashier's window, locking

latches for the blinds and hinged lid, a foot-treadle in juxtaposition to the cashier's window, and means connecting the foot treadle with all of the locking latches. 15

In testimony that I claim the foregoing I have hereunto set my hand at Sheboygan in the county of Sheboygan and State of Wisconsin in the presence of two witnesses. 20

MICHAEL E. FRANK.
